United States Patent Office.

H. LEMAISTRE, OF BRUSSELS, BELGIUM.

Letters Patent No. 75,554, dated March 17, 1868.

IMPROVEMENT IN BELTING.

The Schedule referred to in these Letters Patent and making part of the same.

TO ALL WHOM IT MAY CONCERN:

Be it known that I, H. LEMAISTRE, of Brussels, Belgium, have invented a new and useful Improvement in Belting; and I do hereby declare that the following is a full, clear, and exact description thereof, which will enable others skilled in the art to make and use the same, reference being had to the accompanying drawings, forming part of this specification.

Figure 1 represents an edge view of two ends of belting joined.

Figure 2 is an edge view of the two ends before they are joined.

Figure 3 is a face view of a belt joined, as in fig. 1.

Figure 4 is an edge view of a belt composed of two thicknesses of leather, the ends in each thickness being connected according to my improved plan.

Figure 5 is a face view of the double belt.

Similar letters of reference indicate corresponding parts.

This invention relates to a new method of joining the ends of the leather straps, which compose a belt for machinery, and also in a novel composition for cementing the straps.

The invention consists, first, in tapering the ends of the straps to be united to a fine edge, and in arranging a small cap on one of the straps, at the commencement of the tapering portion, to receive the edge of the other strap. When the surfaces are roughened and covered with a strong cement, the two straps will be firmly connected.

The invention consists, also, in combining gutta percha with sulphuret of carbon, in such manner as to form a strong cement for firmly uniting two pieces of leather.

A represents the end of a leather strap, to be connected with another strap, B, to form a belt. The end of the strap A is tapered to a fine edge, as is also that of the strap B, as shown. On the strap B is also, at the root of the tapering part, formed a tapering lip, *a*, between which and the tapering end *b* a groove is formed. The end of the strap A is fitted into this groove, as in fig. 1, and perfectly smooth surfaces will be formed by the thus connected straps.

Before the straps are connected, the surfaces of their tapering ends are roughened by suitable apparatus, and are then covered with a suitable cement; then the pieces are joined, and when the cement is dry, the pieces will be firmly united. By means of eyelets *c c*, the pieces may be still more firmly connected.

For belts consisting of two or more thicknesses of leather, each thickness, in itself, is composed of pieces of leather, which are joined in the aforesaid manner, as shown in fig. 4. The thicknesses are then laid one upon the other, with the requisite layer of cement between them. The cement by which the leather straps are connected is composed of three parts of gutta percha and five parts of sulphuret of carbon.

The gutta percha should be cut into as small pieces as can conveniently be done, to facilitate its dissolution, and the pieces are then put into a vessel containing the sulphuret of carbon, care being taken that the vessel be not completely filled, so as to allow the swelling of the contents. After from twenty-four to forty-eight hours, according to the degree of heat, the solution will be perfected. The solution is then applied to the roughened surface of the leather, and is allowed to dry thereon before the pieces of leather are joined. When dry, the solution will appear whitish.

When the composition is dry upon the parts to be united, the said parts are held over a heated hearth, and by warming, the cement is again dissolved. When, then, the pieces are brought together, and the cement is left to dry for the second time, they will be firmly united.

I claim as new, and desire to secure by Letters Patent—

1. The manner herein shown and described of uniting pieces of leather for making belts, by tapering their ends and leaving a lip, *a*, on every other end, as described, and uniting them by the means hereinafter described.

2. Cutting the ends of leather straps, substantially in the manner described, so that they can easily be united for belting, as set forth.

The above specification of my invention signed by me, this 19th day of March, 1867.

H. LEMAISTRE.
